FOLDING DOLLHOUSE BOOK

Rose M. Bland, St. Louis, Mo.

Application August 8, 1949, Serial No. 109,129

1 Claim. (Cl. 46—21)

1

This invention relates to toy doll house units for the use and enjoyment of children, and relates more particularly to a toy doll house constructed in the form of a foldable book that may be folded up when not in use by the child, or may be opened up for use so as to represent several rooms separated by partitions, all of said rooms being ornamented or pictured as may be desired.

The chief object of the invention, therefore, is to provide a foldable book or unit of the kind referred to, the same comprising an elongated backing or back strip of pasteboard or any other suitable material, this said back strip being foldably increased, transversely of its length, at equally spaced points, for providing equally dimensioned end walls at the ends of the strip and back walls for representing a number of separate dollhouse rooms, said rooms being demarcated by the said folding creases of the back strip and by partition strips foldably attached at their inner ends to the back strip, at or in the folding creases thereof, whereby the creased back-strip and partition strips may be folded up together in book-like form, or may be opened up and set up in simulation of a toy doll house, with the ends of the strip turned angularly or perpendicularly inward for supporting the unit in upright position and for representing the end walls of the dollhouse, and the interior partition strips may be opened perpendicularly inward to represent and define the several rooms of the doll-house.

Another object of the invention is to provide, in a toy doll house of the kind described, an elongated back-strip of appropriately stiff material, the same being regularly and equally creased, transversely of its length, and alternately on each side of the strip, so as to be foldable compactly together in bellow-like folds.

With the stated objects in view, together with such other objects and advantages as may appear from the following specification, attention is now directed to the accompanying drawing wherein

Figure 1 is a frontal elevation of a foldable toy doll house book, as constructed in accordance with this invention.

Figure 2 is a top plan view of the assembly or unit as shown in Figure 1.

Figure 3 is a view similar to that of Figure 2, showing however outer room closure strips as foldably attached at one end to the outer ends of the room partition strips.

Figure 4 is a perspective view showing the foldable doll house unit as substantially folded up together, for storage when not in use.

In practicing this invention, I provide an elongated back-strip 5 of suitably heavy pasteboard or other suitable material for the purpose, this strip being cut to suitable length and width, and being transversely creased or grooved, alternately at opposite sides thereof, as indicated at 5a and 5b, in regular and equi-spaced relation as shown. Thus transversely creased and demarcated at regular and equi-spaced intervals, it is obvious 10 that the strip 5 may be folded up together, in a bellow-like manner as shown in Figure 4, to a form closely resembling a book, but yet differing from a book in its bellow-like manner of closing up for storage. This manner of folding is 15 made feasible by the mode of alternately creasing or grooving the back-strip on opposite sides thereof, as shown at 5a, 5b. Of course, and in lieu of this method of creasing the back-strip 5, this strip might be cut clear through and 20 parted at these points 5a, 5b, and then the several parts re-joined by means of flexible hinge strips of fabric (not shown) suitably glued in place upon the adjacent margins of the parts.

A number of room partition strips 6, of pasteboard or the like, are hinged and foldably secured at their inner ends to the back-strip 5, at the creased or folding points 5a, 5b, thereof, and these partition strips are thus arranged to open inwardly perpendicularly to the out-stretched 25 back-strip 5, as room defining elements. These partition strips 6 are substantially equal in length to the width of the several divisions of the back strip 5, but may be of lesser height, as may be found desirable.

In setting up this doll-house, the back-strip 5 is straightened out, and then the ends thereof are turned perpendicularly inward for sustaining the device in vertical position upon the floor. The room partition strips 6 are then also turned 30 perpendicularly inward for defining the several rooms 7, 8, 9, 10. If desired, outer room closure strips 6a (Figure 3) may be foldably connected, as at 6b, to the outer ends of the partition strips 6 and to an outer end of the back-strip 5, as 35 turned inwardly, for more completely demarcating and defining the several rooms.

When not in use the entire assembly of foldable back-strip 5, partition strips 6 and outer closure strips 6a, may be collapsed and folded up 40 compactly together, as shown in Figure 4. Also, the inner walls or surfaces of the back-strip and partition strips may be pictured and decorated as may be desired, as indicated in Figure 1, and paste-board toy furniture may be placed therein. 45 Such features however are purely optional and

constitute no inventive feature or claim. Obviously, the number of "rooms" for this doll house may be increased or diminished, as desired, by merely varying the length of the strip 5 and the number of the transverse folding creases 5a, 5b, and the number of the partition strips 6 and 6a.

And while I have here shown and described a particular embodiment of the invention and particular structural features thereof, the same may be changed as desired, within the scope of the claim.

I claim:

A folding doll house book comprising an elongated strip of material of suitable length and width, said strip being creased transversely of its length at five equally spaced intervals from end-to-end, the central crease and the two end creases being formed at one side of the strip and the two intermediate creases being formed upon the opposite side of the strip, whereby the several demarcated portions of the strip may be folded compactly together in a zigzag manner, and with the end portions similarly folded outwardly of the intermediate portions to constitute covers for the book, room partition strips foldably connected at their inner ends to the crease-joints of the intermediate portions of the strip and adapted to open angularly outwardly therefrom to represent

rooms of the doll house with parallel side walls or to fold compactly inwardly with the other portions of the strip when not in use and outer room-closure strips respectively foldably connected at creasing ends to the outer ends of the room partition strips for defining the outer limits of the rooms and all of said room closure strips having their free swinging side edges extending in the same direction when in room-closure positions to provide for opening movements of the room-closure strips at the same side of each room.
